UNITED STATES PATENT OFFICE.

WILLIAM HUGH FORBES AND JAMES GIBSON, OF BOSTON, MASSACHUSETTS.

FLUID-MEASURING APPARATUS.

SPECIFICATION forming part of Letters Patent No. 403,933, dated May 28, 1889.

Application filed January 28, 1889. Serial No. 297,859. (No model.)

To all whom it may concern:

Be it known that we, WILLIAM HUGH FORBES and JAMES GIBSON, citizens of the United States, residing at Boston, in the 5 county of Suffolk and State of Massachusetts, have invented certain new and useful Improvements in Measuring Apparatus; and we do hereby declare the following to be a full, clear, and exact description of the invention, 10 such as will enable others skilled in the art to which it appertains to make and use the same.

Our invention relates to a measuring apparatus; and it has for its object to enable a 15 merchant to expeditiously and easily draw from a cask or other source of supply different standard quantities of liquid without the necessity of handling separate measuring-vessels of different capacities.

20 With this end in view our invention consists of a series of stationary measuring-vessels of different sizes for holding varying quantities of liquid, a conduit common to all of and connected with the series of measuring-vessels and adapted to be connected by a single connection with a cask, barrel, or other source of supply, and valves for controlling the admission of liquid to and its discharge from each measuring vessel or receptacle; and our invention further consists of 25 the peculiar construction and arrangement of devices, as will be hereinafter more fully described and claimed.

To enable others to understand our invention, we will now proceed to describe the same 30 in connection with the accompanying drawings, in which—

Figure 1 is a plan view of our improved measuring apparatus especially adapted for 35 retailing liquids. Fig. 2 is a vertical longitudinal sectional view thereof on the line xx of Fig. 1. Fig. 3 is a vertical transverse sectional view through one of the measuring-vessels on the line yy of Fig. 2, and Fig. 4 is 40 an enlarged detail sectional view of the air-valve and indicator.

Like numerals of reference denote corresponding parts in all the figures of the drawings.

45 Referring to the drawings, 1 2 3 4 designate a series of vertical stationary measuring vessels or receptacles, and 5 is a conduit

or supply pipe common to all of said vessels or receptacles. These receptacles are made of different sizes, so as to contain varying 55 quantities. Thus, the vessel 1 is designed to hold and measure a gallon of liquid, the vessel 2 a half-gallon, and vessels 3 4 a quart and pint, respectively; but the size or capacity of the vessels and the order of arrangement thereof, as shown in the accompanying drawings, are immaterial and can be varied at pleasure without departing from the spirit or sacrificing the advantages of our invention.

65 The conduit or supply pipe is arranged longitudinally above the entire series of vessels, 1 to 4, inclusive, and communicates with all of said series of vessels, an inlet port or opening, 6, being formed in the middle of the 70 upper head of each vessel or receptacle. We prefer to terminate the ends of the conduit or supply pipe immediately above and connect the same directly to the end vessels, 2 and 4, of the series of vessels and to provide 75 openings or nozzles at intermediate points in the length of the conduit for establishing communication between the latter and the intermediate vessels 1, and 3, of the series; but this manner of connecting the conduit 80 and series of vessels can be modified and changed.

The vessels and conduit are suitably connected together, and the vessels are suspended from the conduit, so as to leave the lower 85 ends thereof free to enable suitable receivers to be placed below the measuring-vessels to receive the contents thereof directly from said vessels. The lower ends of the measuring-vessels are flared, as at 7, and provided with central vertical outlet-ports, 8, whereby all of 90 the liquid in the vessel can be expeditiously removed.

Each vessel of the series of measuring-vessels has two valves, 9 10, one valve, 9, being 95 arranged at the upper end of the vessel over the inlet-port 6 thereof, and the other valve, 10, being arranged at the lower end of the vessel over the outlet-port 8 thereof. Each of these valves preferably consists of a flat 100 metallic plate, which is fitted to slide in fixed ways or cleats 11.

In order to expeditiously adjust the valves and keep the same in their proper relative

position to cut off the supply of liquid from the conduit to the vessel when the latter is opened to discharge its contents, and thus prevent more than the proper quantity from escaping, we have provided an intermediate connection between the upper and lower valves of each measuring-vessel, which is so arranged and connected to said valves as to move the same simultaneously in opposite directions. This intermediate connection comprises a vertical lever, 12, and suitable rods, 13 14, between the valves and the ends of the lever. Each lever is bent at an intermediate point of its length, (see Fig. 3,) and fulcrumed at the angle, formed by bending the same, to a short post, 15, which is rigidly secured to the side of the vessel and extends outwardly therefrom a suitable distance. The rods 13 14 are pivotally connected to the lower ends of the operating-lever and suitably secured to the valves, a handle, 16, being provided at the lower end of the lever for conveniently manipulating the latter and the valves connected thereto. The upper connecting-rod, 13, has a packing, 17, secured thereon, which works in a stuffing-box, 18, on the upper side of the measuring-vessel, to effectually prevent leakage of the contents of the vessel through the opening formed in the side of the latter for the passage of said rod, and the rod 13 is further provided at intermediate points of its length with rigid stop shoulders or lugs 19, which are adapted to come in contact with the vessel, and thus limit the reciprocating play or movement of the valves and lever and prevent said valves from being moved past the proper points.

The conduit or supply-pipe 5 has a single nozzle or coupling, 20, for connecting the same to a barrel, cask, or other source of supply from which the liquid can be drawn. This coupling 20 is arranged at the middle of the conduit, and has a stop cock or valve, 21, by which the supply from the cask, &c., to the conduit can be cut off or established at pleasure.

Each measuring-vessel is provided with an air port or aperture, 23, in its upper head, and through this port passes a vertically-movable spindle, 24, which carries a disk, 25, at its lower end, and has a shoulder or flange, 26, at its upper end. This disk, which is preferably made of rubber, is of greater diameter than the air-port through which the spindle passes, and when the liquid in the vessel reaches the disk the latter and the spindle are elevated to indicate that the vessel has received the necessary quantity of liquid. Air can pass freely through the port 23 when the valve is lowered, to enable the liquid to escape from the vessel with greater freedom.

The operation and advantages of our invention will be readily understood from the foregoing description, taken in connection with the drawings.

The conduit or supply-pipe is first connected by its coupling to the cask, &c., and the upper valves of all the vessels of the series are closed, after which the cock or valve in the coupling is opened to admit the liquid from the cask, &c., into the conduit or supply-pipe. When it is desired to draw a certain quantity of liquid—say a half-gallon—the lower end of the operating-lever of the vessel 2 is forced inward, thereby closing the lower valve and simultaneously opening the upper valve of said vessel. Liquid from the conduit is thus admitted and retained in the measuring-vessel until a sufficient quantity has accumulated therein, which is indicated by the vertical displacement of the indicating-spindle, after which the operating-lever is reversed. This reversal of the lever closes the upper valve to cut off the supply of liquid from the conduit to the measuring-vessel, and at the same time opens the lower valve of the vessel to permit the liquid therein to escape through the outlet-port 8 into a suitable receptacle placed beneath the suspended measuring-vessel.

We are aware that changes in the form and proportion of parts and details of construction of the apparatus herein shown and described as an embodiment of our invention can be made without departing from the spirit thereof.

Having thus fully described our invention, what we claim as new, and desire to secure by Letters Patent, is—

1. A measuring apparatus, substantially as described, consisting of a single continuous supply-conduit adapted to communicate with a source of supply, a series of vertical measuring-vessels of assorted sizes suspended from said conduit at intermediate points of the length thereof and each communicating directly with the conduit through a port in its upper end, a valve located within the vessel for opening and closing the inlet-port between the conduit and vessel, and another valve in the lower end of each vessel, substantially as and for the purpose described.

2. In a measuring apparatus, the combination of a vessel having inlet and outlet ports at diametrically opposite ends, and a lateral stuffing-box in the side thereof near the upper end, a reciprocating valve operating over each of the ports, a lever connected directly to the lower valve, and an endwise-movable rod, 13, connected to the lever and upper valve and having a packing and the fixed stops, substantially as and for the purpose described.

In testimony whereof we affix our signatures in presence of two witnesses.

WILLIAM HUGH FORBES.
JAMES GIBSON.
